MOUTH ORGAN

Walter Hohner, Trossingen, Germany

Application March 29, 1950, Serial No. 8,829
In Germany October 19, 1948

Term of patent 14 years

(Cl. D56—12)

To all whom it may concern:

Be it known that I, Walter Hohner, a citizen of Germany, residing at Trossingen, Germany, have invented a new, original, and ornamental Design for Mouth Organ, of which the following is a specification, reference being had to the accompanying drawing, forming a part hereof.

Fig. 1 is a front perspective view of a mouth organ showing my new design; and

Fig. 2 is a rear perspective view thereof.

The drawing has been shaded to show contrasting appearance.

I claim:

The ornamental design for a mouth organ, as shown and described.

WALTER HOHNER.
